Patented Apr. 7, 1959

184,830

TAPE AND PUNCH READER

Harold Eugene North, South Glastonbury, Conn., assignor to Royal McBee Corporation, Port Chester, N.Y., a corporation of New York

Application December 10, 1957, Serial No. 48,854

Term of patent 14 years

(Cl. D26—14)

Fig. 1 is a front perspective view of a tape and punch reader showing my new design; and

Fig. 2 is a rear perspective view of the tape and punch reader shown in Fig. 1.

The broken line showing of the reels, perforated tape, and supporting arms are for illustrative purposes only. The drawing figures are stippled to indicate contrast in appearance.

I claim:

The ornamental design for a tape and punch reader, as shown and described.
